GOLF PUTTER HEAD

Joseph H. Leeah, 5120 Marcillus, El Paso, Tex.

Filed Oct. 7, 1963, Ser. No. 76,878

Term of patent 14 years

(Cl. D34—5)

I claim:

The ornamental design for a golf putter head, as shown.
